UNITED STATES PATENT OFFICE.

JOSEPH S. BARTLEY, OF DENVER, COLORADO.

GRINDING MILL.

Application filed November 14, 1919, Serial No. 338,019. Renewed May 14, 1924.

To all whom it may concern:

Be it known that I, JOSEPH S. BARTLEY, a citizen of the United States, residing at Denver, in the county of Denver and State of Colorado, have invented certain new and useful Improvements in Grinding Mills, of which the following is a specification.

This invention relates to grinding mills of the type commonly known as rod mills 10 in which a mass of loose rods have a tumbling motion in a rotating drum.

The primary object of the invention is to provide in a mill of the above described character, a plurality of loose grinding rolls 15 which are longitudinally fluted to provide rounded teeth or ridges which alternate with furrows or depressions of greater width.

A mass of rolls of this form loosely placed within the grinding cylinder will mesh with 20 each other and with the lifting or tumbling ribs usually provided on the inside of the rotating cylinder, thereby increasing the grinding capacity of the mill and promoting the circulating motion of the material under treatment.

An embodiment of my invention has been illustrated in the accompanying drawings in which—

Figure 1 presents a vertical longitudinal 30 section through a rod mill of the improved construction, and

Figure 2, a transverse section taken on the line 2—2, Figure 1.

Referring to the drawings by numerals, 35 2 designates the grinding drum of the mill which is mounted for rotation about a horizontal axis, upon two pedestals 3. The drum is composed of a cylindrical shell 4 which is closed at its ends by heads 5 and 40 6 provided with central hollow trunnions 7 and 8, resting in pillow boxes 10 on the pedestals 3.

The trunnions 7 carries a scoop 12 for feeding ore pulp or other material in liquid 45 into the cylinder and the opposite trunnion 8 serves for the discharge of the disintegrated product which rises in the liquid and is displaced by the constant inflow of fresh material.

50 Bolted upon the interior surface of the shell are equidistant lifting ribs 13 of rounded section which in the operation of the mill serve to lift the grinding bodies and the material under treatment from the bottom of the rotating cylinder to produce a tumbling and cascading movement thereof.

The grinding bodies of the present invention consist of rolls 14 which are fluted to provide longitudinal teeth or ridges 15 alternating with depressions or furrows 16 60 of greater width.

The lifting ribs 13 and the ridges 15 of the tumbling rolls 14 are relatively large and present rounded projecting surfaces and intervening concave surfaces. The rounded projecting surfaces are of a size to fit between the lifting ribs of the drum and they are 65 equally spaced around the tumbling rolls at an angle of 120 degrees, producing a substantially triangular formation of the tumbling rolls.

The rolls are preferably made hollow for the reception of rods 17 which augment their grinding action and increase their weight.

The rods extending loosely in the bores 75 of the rolls, permit of the passage of material around them and thus cooperate with the rolls to increase their grinding capacity.

The rods furthermore serve as a filler 80 which is readily removed when the roll is worn out, and placed in another roll, thereby preventing the waste of metal which would be unavoidable in case the rolls were 85 solid.

A mass of the rolls placed loosely in a rotating grinding cylinder, have a triturating action upon the material constantly entering through the trunnion 7 at the feed 90 end of the same, by their tumbling and rotating movements.

The outermost rolls of the mass congregating in the bottom portion of the cylinder, mesh with the lifting ribs on the inner circumference of the same and all the rolls 95 contained in the mass intermesh with each other as closely as the presence of the material under treatment permits.

During rotation of the cylinder in the direction of the arrow A, Figure 2, the several 100 rolls are thus lifted to a point of release by gravitation and, together with material carried in their furrows, are caused to drop successively to the bottom of the drum.

The falling rolls meshing with those adjoining, impart a rotary motion thereto which is again transmitted to the next following rolls and so on through the entire mass.

The rotary movement of the cylinder thus 110 produces a continuous cascading movement of rotating bodies and interflowing ore pulp,

with the result that the latter is rapidly disintegrated to the desired fineness.

- It will be seen that the intermeshing parts of the rolls increase their effective grinding surface to a considerable extent, that the engagement of the lifting ribs on the inner surface of the cylinder with the teeth of the crushing rolls insures their positive upward motion to a point of release by gravitation, 10 that the furrows in the rolls serve as carriers to lift the material accumulating in the bottom portion of the cylinder, and that the peculiar form of the rolls permits of their approaching each other sufficiently near to 15 have a direct crushing action upon all the ore between them.

A great advantage is thus obtained over existing machines in which the grinding bodies are of circular section and contact 20 with each other and with the lifting ribs only along tangent lines.

What I claim and desire to secure by Letters-Patent is:

1. In a mill of the class described, the 25 combination of a rotating grinding drum provided at its inner surface with relatively large longitudinal lifting ribs, and a plurality of loose tumbling rolls provided with relatively large ribs disposed in substan-

tially triangular formation and said tumbling rolls being adapted to engage the lifting ribs and mesh with one another whereby they will be rotated by the rotary movement of the drum. 30

2. In a mill of the class described, the 35 combination of a rotating grinding drum provided at its inner surface with relatively large longitudinal lifting ribs, presenting rounded engaging surfaces, and a plurality 40 of loose tumbling rolls filling approximately one-half of the drum and provided with relatively large ribs disposed in substantially triangular formation and presenting rounded projecting surfaces and having intervening concave surfaces. 45

3. In combination, a grinding mill, and a plurality of freely tumbling elongated bars, certain of said bars having longitudinally extending domes or convex portions and certain of said bars having longitudinally extending concaved portions to cooperate with said domes or convex portions, the radii of said convex and concave portions being substantially equal. 50

In testimony whereof I have affixed my 55 signature.

JOSEPH S. BARTLEY.
